IMPULSE REMOTE CONTROL SYSTEM

Fred H. Osborne, Snyder, and John H. Riggs,
Kenmore, N. Y., assignors to The Rudolph
Wurlitzer Company, Chicago, Ill., a corporation

Application December 21, 1946, Serial No. 717,716

3 Claims. (Cl. 177—353)

1

This invention relates to a remote control system of the general character illustrated in Hayslett and Osborne Patent No. 2,387,444, dated October 23, 1945, entitled "Remote Control Apparatus."

Such a system includes a transmitter adapted to generate electrical signals and a receiver to receive said signals for the selective performance of operations in response to the signal.

The embodiment of the present invention, selected for illustration only, in common with that of the aforesaid patent, contemplates the transmission of signals from the transmitter to the receiver and over the power lines supplying power to the same. The signals herein are in the form of high frequency continuous discharge which is interrupted at the wall box transmitter to supply pulsed signals otherwise unmodulated to the receiver. To this extent the effective signal system herein differs from the aforesaid patented system for that provides a continuous signal that is modulated by a second signal of pulsed character and of low frequency. Herein only a pulsed high frequency signal is utilized.

One object of the present invention is to prevent operation at all times of the receiver by signals originating outside of the system.

Another object of the present invention is to provide a simplified means of tuning one or more transmitters simultaneously to which the single common receiver has been previously fixed tuned.

A further object of the invention is to provide a stable frequency of transmission.

One feature of the present invention resides in preventing extraneous signal operation while the receiver is standing by (shown in said patent) as well as preventing extraneous signal operation of the receiver while it is receiving a wanted or desired signal to the end that the latter only is effective upon the receiver for the selection desired. In other words, a false or erroneous signal will not be imposed upon the receiver for selection purposes. Thus the receiver herein at all times is essentially insensitive to extraneous transients of a duration shorter than the coded high frequency pulses imposed on the alternating current supply line.

A second feature of the present invention resides in the tuning of the transmitter or transmitters without the necessity of utilizing meters and by means of a comparatively inexpensive tube installed in the common receiver so that it may be permanently included in the system for comparison use particularly when crystal substitutions are contemplated for repair purposes.

2

A third feature of the present invention consists in providing a simple and inexpensive means, such as a quartz crystal frequency control unit, in the oscillator of the transmitter, for maintaining a constant and stable frequency at the transmitter.

A supplementary feature resides in the inclusion of a multiple position switch or multiple switch means for selectively associating the appropriate capacity for one of a selected group of crystal frequencies so that the necessity for trimming at other than the selected crystal frequency is eliminated.

Other objects and features of the invention will be set forth more fully hereinafter.

The full nature of the invention will be understood from the accompanying drawings and the following description and claims.

In the drawings,

20 Fig. 1 is a diagram showing in conventional form, the impulse transmitter portion of the system.

Fig. 2 is a diagram in conventional form of the impulse receiver.

25 Fig. 3 is a diagram in conventional form of the impulse stepper.

Fig. 4 is a view of the power transformer associated with the stepper mechanism and a view thereof including the latch release and time delay structure associated therewith.

30 In common with the disclosure of the aforesaid Patent No. 2,387,444, dated October 25, 1945, the present invention contemplates the inclusion of a high frequency continuous carrier produced by any wall box upon coin deposition and modulated by coded interruptions, the latter being derived from an impulse generator which may, if desired, be of the general type illustrated in the lower portion of Fig. 2 of said patent.

35 Such a generator modulates or modifies a high frequency carrier wave as by imparting thereto a long pulse and one or more short pulses in accordance with a predetermined code up to the number of possible selections desired.

40 Much of the general description of the foregoing patent applies to the present invention wherefore same is omitted for brevity, although the said patent is formally made a part hereof only insofar as same is not in conflict with that which follows herein. This conflict broadly is that the patented system utilizes a low frequency pulsed signal imposed upon a carrier signal while the present system utilizes a high frequency signal which is interrupted or pulsed. Note the signals, in both instances are not initiated until a

coin is deposited and the selection is made both of which occur at one of the wall boxes.

Referring to present Fig. 1, the same, as stated, discloses diagrammatically the impulse transmitter of the present invention. It will be recalled that in the lower portion of Fig. 2 of said patent two lines lead from the selector station, such as a wall box and from long pulse segments 88-27 and contact blade 29.

Herein, see Fig. 1, line 20 corresponds to the former, line 21 to the latter, although obviously as between ring 90 of said patent and selector first contact, it is relatively immaterial which is connected for output purposes, so long as the receiver actuated impulse stepper is correspondingly wired.

In Fig. 1 herein, 22 and 23 designate power supply lines connected to transformer 24 having secondaries connected to certain terminals of an eleven pole socket 25, with which is detachably associated an eleven pole plug 26. Taps 27 and 28 from the power lines connect to the socket and are controlled by switch 29 which may be of manual or coin actuated type and corresponds to switch 23 of said patent.

Lines 27 and 28 through the plug and socket connect to rectifier tube 30 (6x5 GT/G type) supplying (D. C.) B voltage to the carrier wave generating system. Said lines 27 and 28 also constitute an outlet for coupling coil 31 to the alternating current line.

The high frequency carrier wave generating system includes choke 32, resistance 33, quartz crystal 34, oscillator tube 35 (6v6 GT/G type) or the equivalent, multiple position switch 36, capacities 37a, 37b and 37c, trimmer condenser 38 and inductance 39.

Switch 36 has lobe 36a associated selectively with contacts 37aa, 37bb and/or 37cc, as desired or required, to attain the peaked condition aforesaid. This, as stated, eliminates the necessity for trimming for crystals of other frequencies.

When lobe 36a engages contacts 37bb and 37cc obviously capacities 37b and 37c are in multiple and in the tank circuit. When lobe 36a engages contacts 37aa, 37bb and 37cc, the capacities 37a, 37b and 37c are in multiple in the tank circuit. When lobe 36a engages only contact 37cc the capacity 37c only is in the tank circuit. Thus three different values of capacity can be selectively included in the tank circuit for the crystal selected for use in the oscillator thereby producing an arrangement that permits trimming to peak performance by the trimming condenser 38, since the crystal oscillates on only one frequency. Trimming is effected for any one crystal of predetermined frequency characteristic and preferably the crystal is that used when lobe 36a connects capacities 37b and 37c in multiple.

The circuit herein illustrated thus is capable of keeping the primary of the oscillator tank coil peaked even though the frequency is shifted by inter-changing crystals and using therewith the multiple position switch 36 aforesaid. The circuit herein illustrated is of regenerative character.

The foregoing provides a means for maintaining a constant and stable frequency at the transmitter of the remote control system. The receiver included indicator indicates that the proper crystal has been used with the proper capacity and peak performance is provided. This invention also obviates the necessity of carrying around a signal generator to tune the various transmitters, i. e., several wall boxes in an estab-

lishment, to a common and the selected frequency, for each wall box would have thereon, for the serviceman's convenience, the multiple switch 36 aforesaid and obviously crystal units can be calibrated and like units commonly designated and utilized.

It is furthermore noted that not only are signal generators expensive, heavy and not very rugged, but portable types have a serious frequency drift and such generator requires the use of a skilled technician and for a considerable period, all of which is unnecessary with the present invention.

Reference will now be had to Fig. 2 wherein the receiver is illustrated. In this figure there is illustrated a 12 pole socket 40, and lines 41 and 42 therefrom represent the signal input to the receiver, said lines being connected to the power supply lines to which the receiver and transmitters are connected. Lines 41 and 42 are suitably connected to the house wiring through the stepper (see Fig. 3) to which reference will be had more fully hereinafter. This receiver circuit also obtains voltage for filaments and rectifier from the power transformer, the primary connections being shown in Fig. 3 aforesaid.

In Fig. 2, 43, 44, 45, and 46 designate radio frequency transformer windings, 47 a radio frequency amplifier tube (6SK7 type), 48, 49, and 50 designate radio frequency interstage transformer windings, and 51 a duo-diode-triode (6SQ7 type) tube.

The system includes a dual triode tube 52 (6SN7GT type) directly connected to the normally open relay 55 and the aforesaid tube 51 and is normally at plate current cut off. A tuning eye tube 53 (6U5/6G5 type) is connected as shown. Also illustrated in Fig. 2 is tube 54. The normally open relay 55 is closable only when a "wanted" or desired signal is supplied thereto.

The present invention incorporates the application of a negative voltage, developed by the amplified signals, back upon the control grid of the remote cutoff tube. The effect of the negative voltage on the control grid of the tube 47 is to reduce sensitivity, that is, the gain of the tube. Through appropriate resistance and capacity there is introduced a time constant in the negative voltage. This maintains the negative voltage upon the system between pulses. Accordingly extraneous transients will not produce an extra action of the selecting switch, shown in Fig. 3, nor cause it to hold over, thereby producing a wrong selection.

The separate secondaries of the interstage transformer develop an A. V. C. voltage and develop signaling voltage for operating the relay 55 associated with the selecting switch shown in Fig. 3.

Hence, there herein is a separation of function which is not present in said patent, which patent only provides protection against false signaling from transients when the receiver is standing by, so that herein complete protection against transients at all times is maintained to prevent false signalling thereby.

For a better understanding of the separation of functions reference will now be had to Fig. 2 wherein the receiver circuit grid G of the radio frequency amplifier tube 47 is connected to ground through coils 45 and 46 and through resistors L and M, all in series. If no current is flowing in resistor M, there is no potential drop across resistor M, and the grid G is effectively at ground potential.

The cathode H of the aforesaid tube 47 is connected to ground through the resistor K, and since the plate current of the tube 47 returns to cathode through the resistor K, there is a potential drop across the resistor K, determined jointly by the value of the resistor and the amount of the plate current. Thus there is a potential difference between the grid G and cathode H, the grid G being negative to cathode H.

If a signal of sufficient duration is received by the tube 47 from input lines 41 and 42 said signal is amplified at radio frequency and passed to the duo-diode triode tube 51 through the windings 48, 49 and 50 of the interstage transformer (not numbered). The signal undergoes three separate and distinct actions in tube 51, and serves three separate and distinct functions:

(a) A unidirectional current (the rectified A. C. signal) is produced through the diode F' of tube 51, coil 50, and the resistor M, returning to cathode E through ground connection at X. The direction of the said unidirectional current is upward through the resistor M so that the potential of the upper end of the resistor M is negative with respect to ground, and the negative potential thus obtained is applied to grid G of the aforesaid tube 47 through the filter resistor L and the coils 45 and 46, all in series. The effect of such negative potential is to increase the negative bias of the grid G. The result, therefore, of a signal of proper duration would be to decrease the sensitivity of the tube 47 to such a signal and also to decrease the sensitivity of the tube 47 to signals of short duration, such as transients. In actual use this results in the receiver sensitivity being maintained at a point at which it will pass wanted signals of proper duration but will discriminate against transients. The described condition of insensitivity to transient signals of tube 47 is obtained both during the wanted signal pulses and during the intervals between the wanted signal pulses.

It is also obvious that by proper choice of the value of the resistor K, relative to the potentials developed across the resistor M, the sensitivity of the whole system may be effectively controlled. Thus if the grid G of tube 47 is biased (in the absence of signals) to a point of reduced sensitivity, only strong signals will be effective in producing the chain of events above described, and the relative value of such strong signals with respect to the strength of any expected transients may be predetermined.

(b) A second effect of the signal received by the tube 51 from the tube 47 is to produce a second unidirectional current from diode plate D through coil 45 and the resistors B and C, all in series returning to the cathode E through ground connection at X, and producing a potential drop across the resistors B and C. A portion of this potential is applied to the grid A of tube 51 from the junction of the said resistors B and C. The two resistors B and C are jointly by-passed by the condenser R, which effectively short circuits the said two resistors for signals of short duration, such as transients. In like fashion the resistor C is separately by-passed and short-circuited for signals of short duration by the condenser N. The duration of such periods of short-circuiting action may be controlled by proper choice of the value of condenser N with respect to the value of resistor C alone.

Thus, if any transient signal has not been sufficiently stopped by the above described action 75

of condenser O and resistor M, as previously described, then such remaining portions of the transient signals are effectively blocked from reaching the grid A of tube 51 by the action just discussed. Such signals are, accordingly, not amplified in the triode section of tube 51, so that the remaining portions of the receiver system are actuated solely by the wanted signals, and are not affected by any unwanted signals.

10 It is well-known in the art that when a condenser is connected in multiple with a resistor, such as resistor M and condenser O, or resistor C and condenser N, etc., any currents flowing through the combination will flow principally 15 through the condenser until it be fully charged, and that all the current will flow through the resistor after the condenser has been charged. Thus such a condenser and resistor will constitute a delay circuit, and the period of delay 20 will be determined by the relative values of the two components. In like fashion, as is well-known in the art, when a potential is removed from such paralleled resistor and condenser, the condenser will discharge through the resistor, 25 the time of the discharge being a joint function of the capacitance, the potential, and the resistance employed. Thus such a combination will provide a delay circuit which is automatically self-releasing. If the component parts are properly chosen, as is contemplated herein, and the 30 wanted signals are of such duration that the desired potentials are established across the resistors; similarly, transient signals, which are generally of much shorter duration than the wanted 35 signals (or can be made so herein), do not persist for a sufficient time to establish undesired potentials across the resistors, but on the contrary dissipate themselves in partially charging the condensers and leaking off through the resistors.

40 (c) A third effect of the signal received by tube 51 from tube 47 is to amplify the wanted signal received by the grid A from the rectifier circuit as just described.

The inclusion of tuning eye tube 53 eliminates 45 the necessity of tuning the receiver trimmers with meters. These trimmers are shown as adjustable in Fig. 2. Meters are bulky, quite delicate and expensive. Tube 53 is light, fairly rugged and comparatively inexpensive. It is more than 50 satisfactory as a meter replacement for the danger of burning out is substantially eliminated and it then is always available for use in peaking the receiver to frequency.

Reference will now be had to Figs. 3 and 4 55 wherein the stepper is illustrated and the signal operated system is also illustrated. Herein the twelve pole plug 60 is associated with the twelve pole socket 40 of Fig. 2. 62 indicates the primary of the power transformer having secondaries 63 to 69 inclusive. Across series windings 65 and 66 is the rectifier 70 which may be of 60 selenium type.

Herein there is provided an alternating current pulse relay 71, a stepper coil structure 72, a timing relay 73 and a release latch relay 74. In addition there are nine switches, see Fig. 3, as shown, two of which are of differential three pole type, the others being two pole type, and of these two are normally closed and the others 70 are normally open until a wanted signal is received.

The impressed signal is applied to the stepper power which advances stepper arm 75 over the several contacts (24 being illustrated), each of which is connected by its individual connection

16 to an individual selection mechanism not shown.

In general, the operation of the stepper mechanism broadly is that disclosed in said patent, wherefore it is believed no further detailed description of that illustrated herein is believed necessary.

Having thus described in considerable detail the essentials of the present invention and referred broadly to the prior patent, certain of the distinctions may be emphasized as follows:

The patented system operates on a continuous radio-frequency current modulated by a signal of intermediate (say 400) cycle pulses. The receiver portion of the patented system is responsive thereto and is protected against transients by negative A. V. C. voltage developed by the diode tube and applied to the amplifier tube grid. This negative voltage is on steady during the sending of the wanted signals.

The present system also develops a negative voltage similar to an A. V. C. voltage. Herein the radio frequency signal is not continuous as in the patented system. Therefore, the present invention provides for protection against transients between pulses of the radio frequency signal.

Specifically the interstage transformer, having primary 48 and secondaries 49 and 50, see Fig. 2, by such separation, accomplishes the two fold purpose of actuating relay 55 in the limited time available for actuation and rendering the amplifier reasonably less sensitive during the sequence of pulses.

In detail secondary 50 develops a negative voltage when the receiving system is supplied with energy, which voltage is applied to amplifier tube 47 for the purpose of rendering it less sensitive, especially to extraneous transients during a sequence of pulses. Thus a squelch action results.

Secondary 49, it will be noted, is not tuned. This makes it faster in operation. Secondary 49 is used to develop a D. C. voltage which voltage is used to operate the D. C. amplifier of which the triode 51 is a part. This causes tube 52 to conduct each time a radio frequency pulse is sent.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a remote signaling system of selective type wherein power lines supply alternating current power to a transmitter, a receiver and a stepper, the lines serving as signal channels and

the transmitter applying selected signals of pulsed high frequency type to the receiver for predetermined actuation of the stepper in accordance with the selected pulsed signal, the combination of means normally preventing receiver actuation by line transients while the receiver is standing by and conditioned to pass wanted signals, and a second means normally preventing distortion by line transients of wanted signals and including a circuit for applying negative voltage to the controlled grid of the amplifier tube of the receiver, the negative voltage being effective at all times the receiver is operative, the receiver including an interstage radio frequency transformer with separate secondaries, and a duplex diode-triode tube connected thereto for the purpose described.

2. In combination a receiver having an electrical unit responsive to signal impulses received by the receiver, said unit comprising at least three interconnected sections, a time-delay device operatively associated with the second of the said sections for limiting the response of the first of said sections to responses greater than a predetermined duration, a second time-delay device operatively associated with said second section for limiting the response of the third section to responses of greater than a predetermined duration, said two time-delay devices simultaneously effecting such limiting action, although not necessarily in the same degree, and a separate automatic means associated with each of time delay device rendering the said associated device independently ineffective when signals of greater than the predetermined duration for which that device is arranged to pass are received by said receiver.

3. A system as defined by claim 2 wherein each time-delay device is of self-releasing type.

FRED H. OSBORNE.
